UNITED STATES PATENT OFFICE

THOMAS E. LANDVOIGT, OF WESTMONT, PENNSYLVANIA, ASSIGNOR TO NATIONAL RADIATOR CORPORATION, OF JOHNSTOWN, PENNSYLVANIA, A CORPORATION OF DELAWARE

RADIATOR

Application filed September 25, 1928. Serial No. 308,273.

My invention relates to radiators, and particularly to panel radiators.

In heating rooms, a better distribution of heat is obtained where convection currents are relied upon for distribution of heat from a radiator to the remote parts of the room than is obtained where radiation, alone, is relied upon. The temperature of the radiator must be maintained considerably above the temperature of the remote parts of the room, where radiation is relied upon in order to secure the desired average temperature. In such cases, the radiator is often too hot to permit persons to remain near it.

Radiators heretofore used have generally presented an unsightly appearance due to the presence of a large number of thin ends of radiator columns and intervening spaces which are usually in shadow and serve as dust accumulators.

I provide a radiator unit having a substantially continuously exposed surface of considerable area. This exposed surface may be ornamental to harmonize with the furniture and walls of a room. The rear surface is provided with a series of grooves constituting passageways or stacks for the movement of convection currents behind the radiator unit. This surface usually faces a wall of the room.

The ends of the radiator units taper slightly from the exposed face, and form continuous corners with the exposed surface from the top to the bottom of the radiator so that a plurality of radiator sections may be placed end to end for constituting an assembled radiator.

The subject matter of this case is related to that of my copending application, Serial Number 308,274, filed September 25, 1928, which has now matured into Patent No.

1,804,424, granted May 12, 1931.

The accompanying drawings illustrate the present preferred embodiment of the invention, in which

Figure 1 is a broken side elevational view of a radiator embodying my invention;

Figure 2 is a plan view partially in section of a radiator section;

Figure 3 is a sectional view thereof taken substantially along the section line III-III of Figure 1;

Figure 4 is an end view of a radiator showing one manner of mounting it;

Figure 5 is a similar view of a radiator showing a modification in the manner of mounting; and

Figure 6 is a plan view of an assembled radiator.

Referring to the drawings, a radiator 2 comprises a plurality of radiator sections 4 placed in end-to-end relation. The radiator sections are connected by pipe nipples 5 extending into openings 6 disposed at the top and bottom of each radiator section, such manner of connection being well known in the art.

Each radiator section 4 comprises a central portion 7, the outer surface of which is constituted by a continuous wall 8 that lies in substantially a single plane. The surface of the wall 8 is provided with small grooves 9 and raised portions 10 to correspond to the joints formed between adjacent sections and present a paneled appearance. With this construction, a number of radiator sections may be fastened together in end-to-end relation and the entire outer surface of the radiator present substantially the appearance that would be given were a plurality of short sections used, whose edges terminated at the grooves 9.

The ends 11 of each section are wider than the body portion 7 providing in effect hollow wings at each end of the section and these wings have flat outer faces 12. The openings 6 are formed in the ends 11. The forward edges of the faces 12 are slightly beveled, as at 14, to provide re-entrant surfaces which match up when the radiator is assembled to correspond to the grooves 9. The inner surfaces of the body portion 7 between the portions 11 are provided with a plurality of outwardly extending ribs 15. The ribs 15 define grooves or passages 16 through which air currents move by convection. The irregular contour defined by the ribs 15 increases the radiating surface of the radiator section and also insures that the air in moving over it absorbs the major portion of the heat by convection rather than by radiation.

The heating of the room by radiation in-

volves a thermal gradient throughout the room, from the radiator to the most remote part of the room. A more nearly uniform heating of the room is obtained where the air 5 is passed frequently over the surface of the radiator by convection currents. If it is desired to maintain the same temperature in a room, it is not necessary to maintain the radiator at as high a temperature where convection 10 currents are relied upon as where radiation is relied upon.

Clamping bolts 18 extend longitudinally of the radiator by which the radiator sections 4 are held together. As shown in Fig. 5, 15 brackets 19 extend into the spaces 19a formed between opposing walls of two abutting sections and engage the hubs for the nipples. The brackets 19 are provided with notches 20 for clearing the clamping bolts 18 and are 20 secured to an adjacent wall or other support. Where brackets are used to support the radiator, the latter is particularly adapted for mounting in a recess 21 in a wall 22.

While I have shown the use of two brackets 25 in this figure, it is to be understood that the lower bracket may be omitted if desired. A space is left beneath the radiator and air currents move upwardly between the wall 22 and the flanges 15 and inner surfaces of the wings 30 11 of the radiator. The air moves across the top of the radiator and escapes beneath an overhanging portion 23 of the wall. The radiator may be used alone or with various types of enclosures and space filling fittings 35 having provision for the passage of air currents through the radiator, of which there are many on the market. An example of such a construction is shown in my copending application.

40 Referring to Figure 4, the radiator may also be mounted on legs 24 resting on a floor 25.

Each radiator section is adapted to be used as a complete radiator. By assembling the 45 radiator sections in end-to-end relation and connecting them, a radiator of any suitable length is provided.

While I have shown and described certain preferred embodiments of my invention, it is 50 understood that the invention may be otherwise employed within the scope of the following claims.

I claim:

1. A radiator section comprising a hollow 55 body portion having a surface extending in substantially a single plane, the opposite surface of the body portion being provided with ribs defining a plurality of grooves, and hollow end portions of greater width than the body portion and ribs, said end portions having continuous walls extending at substantially right angles to the continuous surface of the body portion and having openings for the reception of pipe connections.

60 65 2. A radiator section comprising a continu-

ously hollow body portion having a paneled face, an oppositely disposed face having a plurality of ribs defining air passages, and hollow end portions of a width greater than the maximum width of the body portion. 70

3. A radiator section comprising a hollow body having hollow wings at each end thereof and a hollow panel portion between the wings, the space in the wings and the space in the panel being continuous to permit the 75 flow of fluid therethrough, the front surface of the body extending substantially in a single plane, the rear face of the panel portion between the wings having heat dissipating projections thereon. 80

4. A radiator section comprising a hollow body having hollow wing portions at each end thereof and a hollow panel portion between the wings and connecting the wings, the interior of the body providing a continuous fluid circulating space, the front surface of the body extending substantially in a single plane, the rear face of the panel portion of the body between the wings being corrugated, 85 said wings having nipple receiving openings 90 in the end faces thereof which are disposed rearwardly of the panel portion of the body.

5. A radiator section comprising a body portion having front and rear walls spaced from each other, the exposed surface of the 95 front wall extending in substantially a single plane, the rear surface of the body portion being provided with ribs defining a plurality of grooves, and hollow end portions of greater width than the body portion, the space in 100 the end portions communicating with the space between the front and rear walls of the body.

6. A radiator section comprising a body portion having spaced front and rear walls, 105 the exposed surface of the front wall extending in substantially a single plane, the exposed surface of the rear wall of the body portion being provided with ribs defining a plurality of grooves, and hollow end portions of 110 greater width than the body portion and ribs, the space in the end portions communicating with the space between the walls of the body, said end portions having walls extending at substantially right angles to the continuous 115 surface of the body portion.

In testimony whereof I have hereunto set my hand.

THOMAS E. LANDVOIGT.
